CLAIM

The ornamental design for a ram, as shown and described.

DESCRIPTION

FIG. 1 is an isometric view of a ram in accordance with an embodiment of the invention;

FIG. 2 is a right side elevation view of the ram of FIG. 1;

FIG. 3 is a left side elevation view of the ram of FIG. 1;

FIG. 4 is a top plan view of the ram of FIG. 1;

FIG. 5 is a bottom plan view of the ram of FIG. 1;

FIG. 6 is a front end elevation view of the ram of FIG. 1; and,

FIG. 7 is a back end elevation view of the ram of FIG. 1.

The components shown in broken lines in the drawings are for illustrative purposes only and do not form a part of the claimed design.
